(57) **CLAIM**

The ornamental design for a folder as shown and described.

DESCRIPTION

FIG. 1 is a front elevation view of a folder showing my new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a sectional view thereof taken along line 7-7 in FIG. 1;

FIG. 8 is a sectional view thereof taken along line 8-8 in FIG. 1;

FIG. 9 is a sectional view thereof taken along line 9-9 in FIG. 1;

FIG. 10 is an enlarged sectional view thereof taken at line 10 in FIG. 7;

FIG. 11 is an enlarged sectional view thereof taken at line 11 in FIG. 7;

FIG. 12 is a perspective view thereof; and,

FIG. 13 is a perspective view thereof in a state wherein a stopper portion is released.

The dot-dash broken lines depict the bounds of the cross-section views and form no part of the claimed design.

1 Claim, 13 Drawing Sheets
